Primary Examiner — Selina Sikder(74) *Attorney, Agent, or Firm* — Metis IP LLC(57) **CLAIM**

The ornamental design for a switch or a portion thereof, as shown and described.

DESCRIPTION

FIG. 1 is a perspective view of a switch showing our new design;

FIG. 2 is a front view thereof;

FIG. 3 is a rear view thereof;

FIG. 4 is a right view thereof;

FIG. 5 is a left view thereof;

FIG. 6 is a top view thereof; and,

FIG. 7 is a bottom view thereof.

The broken lines shown in the drawing views are for illustrative purposes only and form no part of the claimed design.
